United States Patent Office.

JOHN M. SCHWARTZ, OF PHILADELPHIA, PENNSYLVANIA.

Letters Patent No. 66,402, dated July 2, 1867.

IMPROVED VEGETABLE-CUTTER.

The Schedule referred to in these Letters Patent and making part of the same.

TO ALL WHOM IT MAY CONCERN:

Be it known that I, JOHN M. SCHWARTZ, of Philadelphia, Pennsylvania, have invented an Improved Vegetable-Cutter; and I do hereby declare the following to be a full, clear, and exact description of the same.

My invention consists of a plate, to which is secured a stationary knife, in combination with a plate, which may be so adjusted as to regulate the thickness of the slices cut from the vegetables, the instrument thus constructed being cheaper than and not so liable to get out of order as those in which an adjustable knife is used.

In order to enable others skilled in the art to make and use my invention, I will now proceed to describe its construction and operation, reference being had to the accompanying drawing, which forms a part of this specification, and in which—

Figures 1 and 2 are longitudinal sections of my improved vegetable-cutter, showing the parts in different positions.

Figure 3 is a transverse section on the line 1-2, fig. 1; and

Figure 4 an inverted plan view.

To each side of a board or plate, A, is secured a strip, B, one end of which projects beyond the edge of the plate; and between the projecting ends of the strips fits a plate, A', which vibrates on pins c c, passing through the strips near the ends of the same. The adjacent edges of the plates A A' are a slight distance apart, and are inclined, as shown in the drawing, and to the upper side of the plate A is secured a plate or knife, d, the cutting edge of which is parallel to and almost in contact with the edge of the plate A'. The knife d is secured at such an angle that its cutting edge is a slight distance above the face of the plate A. In a curved cross-piece, D, the opposite ends of which are secured to the side-strips B B, turns a set-screw, F, the upper end of which is secured to but turns freely in a plate, e, attached to the under side of the plate A'. The cabbage or other vegetable is cut by sliding it over the plates so as to bring it against the projecting edge of the knife d, the thickness of the slices which are cut from the vegetable being regulated by turning the set-screw F so as to increase or diminish the distance between the edges of the plate A' and the knife d. By the use of an adjustable plate, A, instead of an adjustable knife, as has heretofore been the practice, the knife may be secured more firmly in its position, the instrument will not be so liable to get out of order, and may be made at a less expense.

I claim as my invention, and desire to secure by Letters Patent—

The plate A, with its knife d, in combination with the adjustable plate A' and the set-screw F, or its equivalent, the whole being constructed and operating substantially as described.

In testimony whereof I have signed my name to this specification in the presence of two subscribing witnesses.
